(57) CLAIM

The ornamental design for a bowl, as shown and described.

DESCRIPTION

FIG. 1 is a top, perspective view of a first embodiment of a bowl of my design;

FIG. 2 is a side view thereof;

FIG. 3 is a top view thereof;

FIG. 4 is a bottom view thereof;

FIG. 5 is a top, perspective view of a second embodiment thereof;

FIG. 6 is a top view thereof;

FIG. 7 is a top view thereof; and,

FIG. 8 is a bottom view thereof.

The broken lines in the drawings form no part of the claimed design. In FIGS. 1, 3, 5, and 7, the uniform shading inside the bowls indicates a contrasting color with the remainder of the bowls, however no particular color is being claimed.
